UNITED STATES PATENT OFFICE.

JOSEPH JOACHIM REIFGRABER, OF ST. LOUIS, MISSOURI.

AUTOMATIC FIREARM.

SPECIFICATION forming part of Letters Patent No. 729,413, dated May 26, 1903.

Application filed March 25, 1902. Renewed April 7, 1903. Serial No. 151,538. (No model.)

To all whom it may concern:

Be it known that I, JOSEPH JOACHIM REIFGRABER, of the city of St. Louis, State of Missouri, have invented certain new and useful 5 Improvements in Automatic Firearms, of which the following is a full, clear, and exact description, reference being had to the accompanying drawings, forming a part hereof.

My invention relates to automatic magazine-firearms; and it consists of the novel construction, combination, and arrangement of parts hereinafter shown, described, and claimed.

My object is to construct an automatic magazine-firearm—that is to say, a firearm that will by the mere act of pulling the trigger and holding it discharge one at a time every cartridge in the magazine.

The principal features of my invention are 15 applicable to machine-guns, infantry-rifles, pistols, and all firearms in which cartridges are used successively from a magazine.

A further object of my invention is to make a firearm of the class described which is simple in construction and operation and in which the recoil is reduced to a minimum.

Figure 1 is a longitudinal vertical section of an automatic magazine infantry-rifle constructed in accordance with the principles of 20 my invention, parts being broken away to economize space. Fig. 2 is a perspective of the stock for the purpose of illustrating the connection between the stock and the barrel. Fig. 3 is a perspective of the barrel 25 for the purpose of illustrating its connection to the stock. Fig. 4 is a sectional detail of the firing-pin and firing-pin hook. Fig. 5 is a perspective of the firing-pin hook. Fig. 6 is a perspective of the breech-bolt with its 30 operating-arms, piston, piston-wings, and firing-pin hook. Fig. 7 is a perspective of the barrel, illustrating the construction of the gas-chamber in which the piston shown in Fig. 6 is placed. Fig. 8 is an enlarged detail 35 showing the parts shown in Fig. 6 and Fig. 7 assembled in operative position. Fig. 9 is a perspective of the trigger. Fig. 10 is a perspective of the sear. Fig. 1^a is a longitudinal vertical section of an automatic quick-firing machine-gun. Fig. 2^a is a sectional perspective through the magazine and breech-bolt chamber, taken on the line 2^a 2^a of Fig.

1^a. Fig. 3^a is a front end view of the breech-bolt. Fig. 4^a is a perspective of the cam.

Referring to the drawings in detail, the barrel 10 has a bore 11 to receive the cartridge 12 and through which the bullet 13 is discharged. The casing 14 is mounted around the breech end of the barrel 10 to form the gas-chamber 15. The gas-ports 16 connect 55 the forward end of the bore 11 to the gas-chamber 15, the rear ends of said ports discharging laterally from the lugs 17, as shown in Fig. 8. The breech-bolt casing comprises the cylindrical portion 18 of the forward end 60 of the stock 19 and the extension 20, extending backwardly from the casing 14, thus forming the breech-bolt chamber 21. The breech-bolt 22 is slidingly mounted in this chamber. The arms 23 extend forwardly from the 65 breech-bolt one on each side of its center. The piston 24 connects the forward ends of said arms, and the wings 25 project forwardly from said piston and normally occupy positions beside the lug 17, as shown in Fig. 8, so that 70 pressure coming through the ports 16 will force said wings laterally to rotate the breech-bolt 22, then press said piston 24 backwardly.

An opening 25^a is formed longitudinally at the top of the extension 20 of the casing 14 75 for the admission of cartridges, and the magazine 26 extends downwardly from the projection 20, the opening 27 of said magazine being in alignment with the opening 25^a, so that clips of cartridges may be passed downwardly 80 through the opening 25^a into the magazine.

A spring 28 is mounted in front of the magazine and extends into the magazine, and near its free end is a curved plate 29, in which the lower cartridge rests, the tension of the spring being exerted to raise the cartridges, so that they may slide into the bore of the barrel one by one by the operation of the breech-bolt. The handle 30 extends upwardly 90 from the forward end of the breech-bolt 22 through the opening 25^a, and when the breech-bolt is in its normal position the handle 30 is tipped laterally into the locking-notch 31, extending from the forward end of the opening 25^a. The expansive coil-spring 32 is mounted in the breech-bolt chamber 21, is connected to the rear end of the breech-bolt 22 and to the stock, so that the tension of said spring is exerted to slide the breech-

bolt forwardly and to rotate or move said breech-bolt laterally, as required to bring the handle 30 into the notch 31 and lock the breech-bolt in its normal position, said spring 5 having a tension laterally as well as expansively.

The firing-pin 33 is slidably mounted in the center of the breech-bolt 22, said firing-pin being fixed upon the forward end of a sleeve 34, which slides through the stop-plate 35. The expansive coil-spring 36 is placed around the sleeve 34 between the firing-pin 33 and the stop-plate 35, as required to snap the firing-pin forwardly to explode the cartridge, and a plug 37 is placed in the rear end of the sleeve 34 and has a squared opening in which the stem 38, carrying the secondary hammer 39, is slidably mounted and held against rotation. The sear-shoulder 40 is fixed upon the rear end of the stem 38, said sear-shoulder being cone-shaped with its point toward the rear and there being a releasing-notch 41 formed in said sear-shoulder.

The trigger 42 is mounted upon the pivot 43 at the rear end of the breech-bolt chamber, and the sear 44 is mounted upon said pivot beside the trigger, said sear being held yieldingly in its hooked position by the expansive spring 45. A lug 46 projects from the sear 44 and engages the rear side of the trigger, so that when the trigger is pulled the sear is operated. A stop 47 projects backwardly from the trigger to engage the stock and limit the backward motion of the trigger, so that the sear may swing backwardly farther than the trigger swings. When the breech-bolt moves rearwardly, the beveled rear face of the sear-shoulder 40 will engage the beveled forward face of the sear 44 and cause said sear to swing downwardly against the tension of the spring 45 until said sear and sear-shoulder interlock. The parts are so assembled that pulling the trigger will not pull the sear 44 out of engagement with the sear-shoulder 40 except when the sear 44 may pass through the slot 41, and the parts are so assembled that the slot 41 is in line for the sear 44 to pass through it only when the breech-bolt has been rotated laterally into its locked position, so that the firing-pin cannot be released to discharge a cartridge except when the breech-bolt is locked. A slip connection between the trigger and the sear 44 allows the sear 44 to pass over the sear-shoulder 40 and lock, but will not allow the trigger to pull the sear 44 out of engagement with the sear-shoulder 40 except through the slot 41.

An extractor 48 is incased in the forward upper part of the breech-bolt and extends forwardly and downwardly to engage the rim of the cartridge, said extractor being spring-actuated. An enlarged ring 49 extends forwardly from the cylindrical easing 18 to receive the rear end of the projection 20, and pins 50 project inwardly from said ring to form bayonet-joints, with the slots 51 in the rear end of the projection 20.

The trigger-guard 52 is rigidly attached at its rear end to the stock, extends downwardly and forwardly around the trigger through the guard 53, and snaps into the seat 54 at the rear of the magazine 26. A slide 55 is mounted in the guard in position to slide up in front of the breech-bolt 22 when the magazine is empty, said slide being moved upwardly by the free end of the spring 28, thus locking the breech-bolt in its rear position, as required to allow the insertion of a new clip of cartridges. A handle 56 extends outwardly from the slide 55 for manually operating the same. A beveled lug forming the cartridge-stop 57 extends backwardly from the piston 24 into the piston-chamber 15.

The operation is as follows: The handle 30 is manually engaged and moved laterally to unlock the breech-bolt by moving the said handle out of the notch 31. Then the breech-bolt is moved rearwardly against the tension of the spring 32 until the spring 28 snaps the slide 55 upwardly in front of the breech-bolt, thus holding the breech-bolt in its rearward position. Then a clip of cartridges is inserted through the opening 25^a into the magazine, thus depressing the spring 28, allowing the slide 55 to fall downwardly to its normal position. When the breech-bolt is moved backwardly, the sear-shoulder 40 interlocks with the sear 44, and when the breech-bolt moves forwardly the firing-pin 33 is held against the tension of the spring 36 and cocked ready to be released when it is desired to discharge the gun. The expansive tension of the spring 32 moves the breech-bolt forwardly, the handle 30 sliding along the right-hand edge of the opening 25^a until the notch 31 is reached, and then the lateral tension of the spring 32 rotates the breech-bolt, bringing the handle 30 into the notch 31 and locking the breech-bolt in the firing position. When the breech-bolt rotates to its locked position, the notch 41 is brought into line with the sear 44, and when the trigger is pulled the sear 44 will pass through the notch 41, thus releasing the firing-pin. The firing-pin snaps forwardly and discharges the cartridge. The bullet is discharged through the bore 11 until the muzzle is reached. Then the gas passes through the ports 16 to the wings 25, moving said wings laterally until the handle 30 is unlocked from the notch 31. Then the gas enters the gas-chamber 15, presses the piston 24 backwardly, thus moving the breech-bolt backwardly against the tension of the spring 32, withdrawing the empty cartridge-shell from the barrel. The spring 28 presses the loaded cartridges upwardly against the breech-bolt and causing the empty shell to fly outwardly by the action of the extractor 48 engaging the rim. The spring 28 presses the cartridges upwardly against the breech-bolt until the breech-bolt is withdrawn beyond the reach of the cartridges. Then the top cartridge will pass upwardly in front of the breech-bolt until it strikes the point of the

firing-pin. At this time the breech-bolt is moving forwardly, and the point of the cartridge will be pressed into the chamber 11. The rear end of the chamber is larger than the bullet and is flaring, so that the cartridge will find its way into the chamber by the pressure of the breech-bolt. The pressure of the gas passes away. The tension of the spring again prevails and moves the breech-bolt forwardly and laterally into its locked position. The point of the second cartridge comes into contact with the beveled lug 57, thus holding the cartridges from being thrown out of the magazine, and as the breech-bolt moves forwardly the upper cartridge is moved into the barrel, and as the breech-bolt moves laterally into its locked position the sear 44 passes through the slot 41, releasing the firing-pin and discharging the cartridge, and this operation is repeated as long as the trigger is held and until the cartridges have been exhausted from the magazine.

In Figs. 1^a, 2^a, 3^a, and 4^a the construction is slightly modified. The magazine 58 is mounted by the side of and above the breech-bolt chamber, and the cartridges are fed from the magazine into the barrel by the escapement mechanism 59. The inner surface of the forward half of the breech-bolt chamber is provided with a broken screw-thread 60, and the periphery of the breech-bolt is provided with corresponding broken screw-threads 61, said breech-bolt being longitudinally slotted, as indicated by 62, to allow the breech-bolt to slide forwardly with the screw-threads 60 in the slots 62, and then when the breech-bolt is moved laterally or rotated the screw-threads 60 interlock with the screw-threads 61, thus providing a stronger locking device than that shown in Fig. 1. The cartridges are fed downwardly into the gun by gravity through the escapement mechanism, as above suggested, and the empty shells are discharged downwardly and forwardly. The breech-bolt is moved forwardly and laterally into its locked position by a handle connected to the cam 63, said cam having teeth 64 to mesh with the screw-threads 61 and an arm 65 to engage in the slot 66 in the lower rear end of the breech-bolt and having worm-teeth or screw-threads 67 to engage in corresponding threads 68 upon the rear lower face of the breech-bolt, so that as the handle is pushed forwardly the cam is rotated in the direction indicated by the arrow. The teeth 64 engage the screw-threads 61, which move the breech-bolt forwardly. The arm 65 engages the slot 66. The teeth 64 disengage the teeth 61, and the worm-teeth 67 engage the teeth 68 to rotate the breech-bolt into its locked position. The operation of the modified construction is identical with that of the preferred construction except in the particulars mentioned, the spring 32 being, of course, omitted as unnecessary. When the breech-bolt is carried forwardly, thus carrying the piston forwardly in the piston-

chamber, the piston acts as a pump to force the gas and air forwardly through the ports into the bore of the gun, thus cleaning out the ports and bore and cooling the gun. The backward action of the breech-bolt in the pressure of the gas through the ports serves to lessen the recoil. The larger the breech-bolt in proportion to the size of the gun the more the recoil is reduced.

75

I claim—

1. An automatic magazine - firearm comprising a suitable framework; a barrel having a bore in which the cartridge is exploded and through which the bullet is discharged; a casing forming a gas-chamber around the breech end of said barrel; ports connecting the gas-chamber to the forward end of the barrel-bore, said ports discharging laterally into said gas-chamber; a breech-bolt casing extending backwardly from the gas-chamber casing and communicating therewith; a breech-bolt slidably mounted in the breech-bolt casing; arms projecting forwardly from the breech-bolt into the gas-chamber; a piston attached to the forward ends of said arms and operating in said gas-chamber; wings extending from said piston to receive the lateral pressure from said gas-ports to rotate the breech-bolt; means of locking the breech-bolt in its forward position by lateral motion, the lateral motion given said wings by the gas-pressure serving to unlock the breech-bolt and the pressure of the gas upon said piston serving to remove the breech-bolt backwardly to expel the empty shell, said gas-pressure coming from the cartridge explosion through said gas-ports; means of moving the breech-bolt forwardly and rotating it to its locked position thereby inserting a new cartridge and cocking the firing-pin, a firing-pin slidably mounted in the breech-bolt; a spring for snapping the firing-pin forwardly to explode the cartridge; a sear-shoulder on the firing-pin; a trigger; a sear yieldingly connected to the said trigger to engage the sear-shoulder to cock the firing-pin, said sear and sear-shoulder interlocking so that the firing-pin cannot be released except by rotating the breech-bolt into its locked position; a cartridge-magazine; and means of feeding the cartridges one at a time, to the barrel, substantially as specified.

2. In an automatic magazine-firearm, a barrel having a bore in which the cartridge is exploded; a casing forming a gas-chamber around the breech end of the barrel; ports connecting the gas-chamber to the barrel-bore, said ports discharging laterally into the gas-chamber; a breech-bolt casing extending backwardly from the gas-chamber casing, and communicating therewith; a breech-bolt slidably mounted in the breech-bolt casing; a piston extending from the breech-bolt into the gas-chamber; wings extending forwardly from the piston to receive the lateral impact of the gas; means of rotating the breech-bolt

into its locked position, the lateral pressure of said gas serving to unlock the breech-bolt, substantially as specified.

3. In an automatic magazine-firearm, a barrel having a bore in which the cartridge is exploded, and through which the bullet is discharged; a casing forming a gas-chamber around the breech end of the barrel; ports connecting the gas-chamber to the forward end of the barrel-bore; said ports discharging laterally into said gas-chamber; a breech-bolt casing extending backwardly from the gas-chamber and communicating therewith; a breech-bolt slidingly mounted in the breech-bolt casing; arms projecting forwardly from the breech-bolt into the gas-chamber; a piston attached to the forward ends of said arms, and operating in said gas-chamber; wings ex-

tending from said piston to receive the lateral pressure from said gas-ports to rotate the breech-bolt; means of locking the breech-bolt in its forward position by lateral motion, the lateral motion given said wings by the gas-pressure serving to unlock the breech-bolt, and the pressure of the gas upon said piston serving to move the breech-bolt backwardly; and means of feeding cartridges into the bore in front of the breech-bolt, substantially as specified.

In testimony whereof I affix my signature in presence of two witnesses.

JOSEPH JOACHIM REIFGRABER.
